UNITED STATES PATENT OFFICE.

PATRIK WALDEMAR LARSSON AND OSKAR EDVIN FORSBERG, OF GOTTERBORG,
SWEDEN, ASSIGNEES TO AKTIEBOLAGET PRINCEPS, OF GOTTERBORG, SWEDEN, A
CORPORATION OF SWEDEN.

PRESS FEEDING.

Application filed January 5, 1925, Serial No. 477, and in Sweden July 7, 1924.

This invention relates to printing presses with automatic feeding of the sheets and has for its object to provide a device for obtaining an exact lateral registering of the sheets, and other improvements.

When feeding the sheets into a printing press a proper registering is of great importance especially in cases where several prints have to be impressed upon the same sheet and for this purpose has to pass through the printing operation more than once. The front registering generally becomes satisfactory in a press with automatic feed, whereas the lateral adjustment of the sheets before these are caught by the grippers often times is less exact although the sheets be taken from an originally evenly made up pile.

The characteristic feature of this invention is that a suction-foot in communication with a suction apparatus is suspended above the sheet to be fed into the printing press and so arranged as to be lowered down to and moved along the surface of the sheet and thus force the same laterally against a stationary rule or square on the feeding table before the sheet is seized by the gripper.

A further object of the invention is to provide means for adjusting the force of the sucking power of the suction-foot to avoid wrinkling the sheet against the stationary rule.

In the accompanying drawings:

Figure 1 shows a front view of the lateral alignment device;

Figs. 2 and 3 show the suction-foot mechanism in front and side views, partly in section;

Fig. 4 is a side view of the entire magazine and feed mechanism with one side standard removed;

Fig. 5 is a front view of part of the feed table;

Fig. 6 is a similar view of the feed ruler and suction pipe, with the lateral adjustment omitted for clearness;

Figs. 7, 8 and 9 are side elevations of the transmission for feeding up the pile of sheets.

In the embodiment of the invention selected for illustration, guide bar 1 is fixedly mounted on the magazine so that it is held in a substantially constant position relative to the sheet that is to be fed. A lever 2 is ro-

tatably mounted at one end of the bar 1 and is provided with a roller 3 at one end and connected in the other end to a sliding bar 6 by means of a link 5. The roller 3 is adapted to periodically engage a cam surface 4. The bar 6 slides in guides 7 fixed to the guide bar 1. The return movement of the bar 6 is performed with the aid of a spring 32 fixed between the bars 1 and 6. By this means the roller 3 is held against the cam 4 and bound to follow its curved or inclined surface. A carrier 8 is adjustably mounted on the sliding bar 6 and can be fixed in place by means of a set screw 12. The carrier 8 accommodates the shaft of a suction-foot 9, which can be vertically moved downward in the carrier against the tension of a spring 10. The shaft of the suction-foot is preferably surrounded by a sleeve 26 provided at the lower end with a collar 28 and at the top with a ring 11. The spring 10 abuts against said ring and the carrier. In the carrier 8 a lever 13 is rotatably mounted on a pin 15 and provided with a cam surface 14 on the upper edge and oblong holes at the free end to engage a pin 16 in the sleeve 26. An adjustable support 17 is clamped by set screw 31 to the guide bar 1, and carries a pivoted stop disc 18 on pin 27. The disc 18 is provided at its lower edge with a cam surface 19 of a suitable form and so mounted in the path of the suction-foot that said cam surface engages the cam surface 14 when the sliding bar is moved towards the left in the drawing. As a pin 20 in the stop 17 prevents the disc 18 from swinging to the left, the cam 19 exerts a pressure against the cam surface 14 during the movement of the suction-foot to the left, so that the lever 13 is depressed and turns around the pin 15 to force the foot down to touch the paper sheet. Towards the end of the movement of the foot to the left the cam surface 14 is released as soon as it has passed the cam surface 19 and the foot is raised by the spring 10. During the return movement of the bar 6 the cam 14 pushes the disc 18 away so that the disc swings around its pin upward and back again to its lower position ready for the next operation when the bar 6 makes another movement to the left. The shaft of the suction-foot is hollow and connected to a suction pipe 21, and the suction-foot is provided with a number of per-

forations 22. The shaft of the suction-foot is threaded at the upper end and provided with nuts 29 by means of which the vertical position of the foot is adjusted. A spring 30 is provided around the lower part of said shaft. By this means the suction foot becomes resilient when it is lowered by the sleeve 26 and touches the sheet of paper.

When a sheet 33 on the table 34 is to be adjusted in its lateral position the suction foot is first lowered down to the sheet and the pump starts its sucking action, then the foot is moved along the surface of the sheet towards the stationary rule, the sucking power ceases during the continued movement of the foot along the surface, and the foot is then raised from the sheet when said sheet is seized by the gripper.

Usually the vacuum pumps operated by the printing press work in such a manner that they create a sucking in the suction pipes during half a turn of the press. The force of said sucking can be controlled in a known manner by means of an adjusting screw on the pump and also by adjusting the length of the stroke of the pump. However a more exact control is required for the purpose here set forth, especially in such cases where paper sheets of different thicknesses are to be printed. For a thick and heavy paper a more powerful sucking is required and for a thin and light paper a less powerful sucking. If a very thin sheet of paper is to be printed and for this purpose moved by the suction-foot close up to the stationary rule without wrinkling the paper we prefer to operate the device in such a way that the suction-foot when lowered down against the sheet of paper 33 to be printed attains such a position at the edge of the sheet that some of the perforations come outside of said edge leaving said perforations uncovered to allow the air to pass therethrough and thus lower the suction power of the foot, see Fig. 2.

However a satisfactory control can be performed also in the following manner. After setting the suction foot on the bar 6 so that it will touch a spot on the sheet 33 that is close to the edge of the sheet the press is started as well as the sucking action and the foot is moved along the surface of the sheet towards the edge and over said edge, which successively uncovers one hole 22 (or row of holes) after the other during the continued movement of the foot. The sucking action ceases and the foot is raised. During said movement along the sheet the sucking power decreases successively when the sheet is moved towards the stationary rule.

As described, the suction-foot can be fixed in any desired position on the sliding bar 6 and is preferably so located that the foot when lowered down against the sheet comes upon or closely to that edge of the sheet which is nearest to the rule 23, said rule

being split so as to allow the foot to pass therethrough as shown in Fig. 3.

When more than one sheet is to be printed simultaneously in the same press and several piles of sheets therefore are placed on the feed table, a corresponding number of suction-feet have to be provided on the sliding bar 6 as well as stops 17 on the guide bar 1.

When using two piles of sheets on the tables 34, 34' simultaneously the sliding bar 75 is preferably divided in two bars 6, 6' arranged to move in opposite directions, so that the suction-foot 9' is moved to the right against the rule 23'. The two bars 6, 6' are linked together by means of two links 24 and 80 the two-armed lever 25, which is rotatably fixed to the guide bar 1. The bar 6' is carried by guides 7' and the suction-foot 9' is operated by a stop 17'. If now only one pile of sheets is used, one of the feet 7, 7' can be put out of operation by turning the corresponding stop-disc 18 or 18' upwards, see Fig. 1, in which position the disc is held by the pin 20' in the stop 17'. By this arrangement the parts are saved from wear.

In installing the device shown in the Figs. 1, 2, and 3, the cam 4 is fixed to the frame of the press and the pins 35 are fixed to the magazine 36, which is carried by arms 37 depending from shaft means 38. The lateral feeding device is shown in Fig. 5 when the suction-foot 9 is just ready to return to its upper position. The shaft 38 is carried by an arm 39, which is swingably mounted on a shaft 40 fixed between two uprights 41 in the machine frame 46. The free end of the arm 39 carries a roller 43 actuated by a cam 42, which is fixed to a shaft 44 in the machine frame. The shafts 38, 40 and 44 as well as a shaft 45 extend between the two uprights 41 and the magazine 36 with its tables 34, 34' is located between the same uprights.

The magazine 36 consists of two angle pieces 47, each one fixed to one arm 37 and to a common back piece 48, which is machined so as to afford an even surface for the back edge of the tables 34, 34', when they move in relation to the magazine. The lower end of the back piece 48 is provided at either side with bearing plates 49 co-acting with rollers 50 carried by brackets 51 on the frame 46. The rollers 50 are so positioned that the point of gravity of the magazine with the arms 47, tables 34 and other accessories is located between vertical planes through the shaft 38 and the plates 49, or at least to the left of a vertical plane through the shaft 38. Thus the magazine always bears against the rollers 50.

Each one of the angle pieces 47 carries two ears 52 through which a long rod 53 can be moved up and down. The rod 53 carries a table 34 by means of a bracket 54 and is suspended by means of a rack bar 55

engaging the toothed shaft 38. The table 34 can thus be raised and lowered by turning the shaft 38 and this can be effected without interfering with the raising and lowering of the magazine 36 by means of the bars 37. However, as both the arms 37 and the bars 55 are carried by the shaft 38, they will move with said shaft intermittently during the periodical rocking movement of the cam 42. The reason for raising the table in the magazine is to always obtain the same level for the top sheet whether the pile of sheets be large or small so that the top sheet conveniently can be seized and held by the suction pipe 56. To cushion the motion to the table, it is provided with a centre pin adapted to slide in the bracket 54 and with a helical spring 57 arranged between the table and the bracket, to carry the weight of the table. The upward movement of the table in the bracket is limited by a washer provided at the lower end of the pin.

Fig. 4 shows the location of the parts when the magazine is raised to its upper position. In this position the suction pipe 56 attracts the top sheet 33 and holds it until the magazine has been lowered and the sheet seized by the gripper as well known in the art.

A bar 58 is fixed to the magazine by means of brackets 59 and carries the stationary rules 23 which can be set in any desired position by the screw handle 60. The rules 23 extend through slots in the tables 34. The sheets are withdrawn from the pile 33 one by one, thereby lowering the height of the pile successively. This lowering has to be compensated in order to get the top sheet properly located under the suction pipe 56 each time a new sheet has to be seized. The device used for said compensation is illustrated in Figs. 4, 7, 8, and 9, in which the parts are shown in different positions to show the action.

The ratchet wheel 61 is fixed to the shaft 38 and driven by pawl 62, which is rotatably mounted on an arm 78 fixed to the shaft 45. A catch 63 stops the backward movement of the ratchet wheel. A rocking movement is imparted to the shaft 45 at each revolution of the press by means of a three armed lever fixed to the shaft with one arm and operated by another arm by a cam 65 fixed to the shaft 44 and co-acting with the roller 66 on said other arm of the lever 64. The third arm is provided with a roller 67 co-acting with one arm of a two armed lever 68, which is fixed to a pin 69 rotatable in the upright 41. A hook 70 is fixed to the pin 69 and co-acts with a tail 71 on the pawl 62. The second arm of the lever 68 is linked to a rod 72 carrying a feel ruler 73 and a pivoted pick 74, which latter co-acts with a boss 75 on a bracket 76 fixed on the upright 41. The rod 72 is guided by the

bracket 76 at its lower end. A spring 77 between the rod 72 and the bracket 76 tends to press the lever 68 against the roller 67.

The action of the pawl 62 will now be described. However, it might be recalled that two tables 34, 34', in one magazine are mounted between the two uprights and carried by two arms 37 and two rack bars 55, but that only one cam 65, one cam 42, one arm 39 and one lever 64 are necessary for the machine. All these parts are mounted between the uprights 41. Outside the frame or uprights there are located the ratchet wheels 61 with ratchets 63 and pawls 62, also the hooks 70. Bars 72 with levers 68 and feel rulers 73, picks 74 and brackets 76 are provided for each table 34, 34' and are mounted inside the uprights. In order to raise the tables 34, 34' successively and independently of each other, the shaft 38 is divided into two parts and provided with a coupling in case the tables are to be operated simultaneously, which occurs when only one pile of large sheets occupies the surface of the two tables. On one end of the shaft 40 the arm 39 is formed as shown in Fig. 4, on the opposite end the horizontal portion carrying roller 66 is omitted.

The pawl 62 can take two positions in relation to the arm carrying it by means of a suitable yielding stop 82, one position as shown in the Figs. 4, 7, and 8, another one as shown in Fig. 9. The feel ruler 73 rests on the uppermost sheet in the pile of paper 33 when the magazine 36 is raised. When the magazine is lowered again the feel ruler 73 rests on one of the arms of the pick 74. The weight and position of the pick 74 is such that the feel ruler 73 can overcome the weight and swing the pick 74 with its notch 79 to one side of the boss 75, as shown in the Figs. 8 and 9. When the feel ruler 73 has been lifted by the paper pile so much that it leaves the protruding arm of the stop 74 the stop swings inwardly over the boss 75, but when the height of the paper pile is so small that the feel ruler does not leave the stop 74, the notch 79 remains beside the boss 75.

Suppose that the pile is high enough to allow the suction pipe 56 to attract the uppermost sheet and no feeding of the wheel 61 is necessary, then the parts will take the positions shown in Figs. 4 and 7. In Fig. 4 the notch 79 rests on the boss 75 and the lever 64 is raised to its uppermost position without producing any rotation of shaft 38. In Fig. 7 the lever 64 has reached its lowermost position and the roller 67 has pressed the surface 80 of the lever 68 downwardly and raised the rod 72 with the notch 79 somewhat above the boss 75. If the pile still is high enough there will be no swinging out of the pick and therefore no lowering of the rod 72 and no swinging of the hook 70 to

the left, but as soon as the pile is too small then the feel ruler 73 takes a lower position and moves the notch 79 outside the boss 75 so that the pick takes the position shown in Fig. 8 and the spring 77 lowers the rod 72 thereby turning the pin 69 and swinging the hook 70 to the left. The hook thereby engages the tail 71 of the pawl 62. The lever 64 now continues its upward motion, the hook 70 is maintained in its position and the pawl is turned to engage the ratchet wheel 61 as shown in Fig. 9 and feed same during the further upward movement of the lever 64. On the return movement of the lever 64, the tail 71 passes the hook 70 but abuts against a projection 81 on the hook so that said projection during the further downward movement of the lever 64 swings the pawl back to the position shown in Fig. 7. This action is repeated and the table 34 moved upwardly by the feed of the wheel 61 until the pile of paper has attained such height in the magazine that the feel ruler 73 does not swing the pick any more.

25 As seen in Fig. 4, the roller does not engage the lever 68, thereby allowing the notch 79 to rest upon the boss 75. In Fig. 7 the lever 64 has attained its lower position and the roller 67 has pressed the arm 68 somewhat downwardly thereby raising the notch 79 from the boss 75. This releases the pick so that the feel ruler can swing it.

It should be noticed that cam 65 registers with the outer well of cam 42, so that the feeding of the tables 34, 34', i. e., the operation of the ratchet wheel 61 by the pawl 62, takes place only when the magazine has been raised by the cam 42 to its upper position.

Without further elaboration, the foregoing will so fully explain the gist of our invention that others may, by applying current knowledge, readily adapt the same for use under various conditions of service, without eliminating certain features which may properly be said to constitute the essential items of novelty involved, which items are intended to be defined and secured to us by the following claims.

We claim:—

50 1. In automatic feeding apparatus for printing presses, a device for the lateral registering of the sheets consisting of a suction-foot in communication with a suction apparatus and mounted in a carrier on a longitudinally movable sliding bar adapted to be reciprocated by means operated from the driving mechanism of the press, a stop arranged in the path of the suction-foot so as to move same in the carrier transversely to the bar, and stationary rule at one end of the sheet.

2. In automatic feeding apparatus for printing presses a device for the lateral registering of the sheets consisting of a suction-foot in communication with a suction

apparatus, a carrier surrounding the shaft of said suction-foot and adjustably mounted on a longitudinally movable sliding bar, means to reciprocate said sliding bar, guides for the sliding bar fixed to a guide bar 70 mounted in a substantially fixed relation to the surface of the sheet to be fed, a stop adjustably mounted on the guide bar in the path of the suction-foot, a spring operating the suction-foot against the pressure 75 from the stop, and a stationary rule at one of the sheet.

3. In automatic feeding apparatus for printing presses a device for the lateral registering of the sheets consisting of a guide bar mounted in a substantially fixed relation to the surface of the sheet to be fed, guides fixed to said guide bar, a longitudinally movable sliding bar in said guides adapted to be reciprocated by means operated from the driving mechanism of the press, a carrier adjustably mounted on said sliding bar, a suction-foot with a shaft adapted to slide in said carrier, said shaft being hollow and communicating with a suction apparatus, a lever rotatably mounted around a pin in said carrier and provided with a cam and an oblong hole to accommodate a pin in the said shaft of the suction-foot, a pivoted stop adjustably mounted on said guide bar in the path of the suction-foot when the sliding bar is reciprocatingly moved, means for reciprocating the sliding bar, and a spring operating the suction-foot against the pressure from the stop when the suction-foot is being moved in one direction against a stationary rule at one end of the sheet, the stop being so arranged that it swings around its pivot without operating the suction-foot when same is moved in the opposite direction.

4. In automatic feeding apparatus for printing presses, a device for the lateral registering of the sheets consisting of a guide bar mounted in a substantially fixed relation to the surface of the sheet to be fed, guides fixed to said guide bar, two longitudinally movable sliding bars in said guides adapted to be reciprocated in opposite directions to each other by means operated from the driving mechanism of the press, a carrier adjustably mounted on each of said sliding bars, each one of said carriers surrounding the shaft of a suction-foot, said shaft being hollow and in communication with a suction apparatus and being adapted to move up and down transversely to said sliding bar, a stop arranged in the path of each of the suction feet so as to periodically move the feet vertically against the sheets to be fed each time the feet pass said stops in one direction against a stationary rule at one end of the sheet, the stops being pivoted so as to swing out of the way when the feet move in the opposite direction.

5. In combination in automatic feeding apparatus for printing presses, a support for a pile of sheets, a suction member associated therewith, a gauge element, means for lowering the suction member into engagement with the surface of the top sheet of the pile and for then moving it toward the gauge element to force said top sheet laterally against the said gauge element, and means for varying the suction exerted on the top sheet by the suction member to prevent wrinkling of the sheet.

6. In combination in automatic feeding apparatus for printing presses, a support for a pile of sheets, a suction member having air inlets associated therewith, a gauge element, and means for moving the suction member into contact with the top sheet of the pile with part of its inlets exposed over an edge of the pile and for moving said suction member to bring the said top sheet laterally against the said gauge element.

7. In combination in automatic feeding apparatus for printing presses, a support for a pile of sheets, a suction member, a gauge element, and means for lowering the suction member into contact with the top sheet of the pile, for moving said suction member to bring the said top sheet laterally against the said gauge element, and for automatically relieving the suction applied to the said top sheet by the member before the member is moved out of contact therewith.

8. In combination in automatic feeding apparatus for printing presses, a support for a pile of sheets, a suction member having air inlets associated therewith, a gauge element, and means for moving the suction member into contact with the top sheet of the pile with part of its inlets exposed over an edge of the pile and for moving said suction member to bring the said top sheet laterally against the said gauge element, said means automatically relieving the suction applied to the said top sheet by the member before the member is moved out of contact therewith by moving said member further over the edge of the pile exposing more of the inlets thereof.

9. In combination in automatic feeding apparatus for printing presses, a support having thereon a sheet of paper, a gauge therefor, a suction member having air inlets associated therewith, means for moving the suction member into contact with the sheet of paper with part of the inlets exposed over an edge of the sheet and for moving the sheet into register with the gauge, and means for adjusting the position of the suction member to vary the number of air inlets thereof exposed over the edge of the paper.

In witness whereof, we hereunto subscribe our names this 10th day of December, 1924.

PATRIK WALDEMAR LARSSON.
OSKAR EDVIN FORSBERG.
